UNITED STATES PATENT OFFICE.

JOHN B. ESTEP, OF CLEVELAND, OHIO.

PIPE HANGER.

Application filed April 10, 1922. Serial No. 551,231.

To all whom it may concern:

Be it known that I, JOHN B. ESTEP, a citizen of the United States, residing at Cleveland, in the county of Cuyahoga and State 5 of Ohio, have invented a new and useful Pipe Hanger, of which the following is a specification.

This invention relates to improvements in pipe-hangers, and pertains more especially 10 to a pipe-hanger adapted to be used in supporting a pipe and comprising a pipe-embraceable metal strap and a supporting member for said strap.

One object of this invention is to secure 15 the component members of a pipe-hanger of the character indicated together without the use of bolts, screws, nuts, rivets or similar securing devices.

Another object is to facilitate the manufacture and assemblage of said component members, and to render my improved hanger simple, strong and durable in construction. 20

With these objects in view, and to attain any other object hereinafter appearing, this 25 invention consists in certain features of construction, and combinations and relative arrangements of parts, hereinafter described in this specification, pointed out in the claims, and illustrated in the accompanying 30 drawings.

In said drawings, Figure 1 is a side elevation illustrative of my improved pipe-hanger shown as participating in the support of a substantially horizontal pipe. 35 Fig. 2 is a vertical section taken along the line 2—2 in Fig. 1. Fig. 3 is a horizontal section taken along the line 3—3 in Fig. 1, looking downwardly. Fig. 4 is a vertical section taken along the line 4—4 in Fig. 1. 40 Fig. 5 is a vertical section taken along the line 5—5 in Fig. 2. Fig. 6 is a horizontal section taken along the line 6—6 in Fig. 1, looking upwardly.

Referring to said drawings, 10 indicates a 45 substantially horizontal pipe in the support of which my improved pipe-hanger is shown as participating, and said hanger comprises a flexible metal strap 12 which is shown as extending under and thereby forming a seat 50 for said pipe. The strap 12 has two opposite flexible side portions 13 arranged and contoured as required to extend transversely of and embrace opposite sides respectively of the pipe 10 and spaced at their upper ends, 55 as shown in Fig. 2. Each side portion 13 of said strap terminates, at its upper end, in a

substantially vertically upwardly projecting arm 14.

A supporting member, preferably consisting of a substantially vertical metal strip 15, 60 is shown as supporting the strap 12 and adapted to be suspended from a supporting object (not shown) and has its lower end portion extending between the arms 14. Said portion of the strap-supporting strip 65 15 is provided, between the arms 14 of the strap 12, with a hole 16 extending laterally through said strap-supporting strip. Preferably said hole 16 is in the form of a rectangular slot extending endwise of the 70 strip 15 and having a substantially horizontal bottom wall and a top wall which is substantially parallel with said bottom wall.

Each of the arms 14 has a tongue 18 which 75 projects through the slot 16 and into an aperture 20 formed in the other of said arms, and the bottom wall of said slot 16 forms a seat for said tongue which is arranged to rest on said wall. The tongue 18 80 of each of the arms 14 is provided, within the other of said arms, with a projection 21 extending below the slot 16, and said slot extends somewhat farther above the tongues 18 of the arms 14 than the projections 21 of 85 said tongues extend below said slot when the tongues rest on the bottom wall of said slot.

By the hereinbefore described construction it will be observed that each of the arms 14 is apertured as required to accommodate 90 the reception of the tongue 18 of the other of said arms, and I would here remark that the tongue 18 of each arm 14 is preferably formed by a laterally struck portion of said arm and trimmed or contoured as required 95 to form the projection 21 of said tongue, and that said laterally struck portion is arranged to be seated on edge on the bottom wall of the slot 16 in the strap-supporting strip 15. The tongue-forming laterally 100 struck portions 18 of the arms 14, as shown in Fig. 5, are arranged side by side in the slot 16, and each of said portions 18 is in close proximity, at its outer side, to the adjacent side wall of said slot.

The aperture 20 in each arm 14 is preferably rectangular and extends endwise of the arm, and the outer end portion of the tongue 18 of each of the arms 14 is arranged wholly within the aperture 20 of the other 110 of said arms. The top wall of the aperture 20 in each of the arms 14 is in close relation

to and overlaps the top edge of the tongue 18 of the other of said arms. The apertures 20 in the arms 14 preferably extend somewhat below the projections 21 of the tongues 18, and it will be observed that, when said tongues are seated on the bottom wall of the slot 16 in the strap-supporting strip 15, the projection 21 of the tongue 18 of each arm 14 cooperates with the adjacent portion of 10 said strip in retaining said arm in proper position in relation to said strip, but in order to insure the holding of the arms 14 in close relation to said strip a collar 22 is provided.

15 The collar 22 preferably consists of a substantially horizontal metal plate having a rectangular slot 23 formed substantially centrally of and extending vertically through the plate, and said plate is arranged above 20 the elevation at which the pipe 10 is shown held, and the arms 14 extend through said slot. It will be observed that the strap-supporting strip 15 has its lower end portion centrally between the side walls of the slot 23 in the collar-forming plate 22, that opposite sides of said portion of said strip are spaced from and face in the direction of opposite side walls respectively of said slot, that each side wall of said slot is in close 30 relation to the adjacent arm 14 which extends between said wall and said strip, and that the plate or collar 22 is not only below the slot 16 in said strip but arranged below the apertures 20 in the arms 14 and consequently below the projections 21 of the 35 tongues 18 of said arms.

The collar 22 is removable upwardly from the arms 14, and obviously the flexibility of the side portions 13 of the strap 12 permits 40 said arms, upon lifting the strap 12 far enough to bring the projections 21 of the tongues 18 above the bottom of the slot 16 in the strap-supporting strip 15 after shifting said collar far enough upwardly above 45 the arms 14, to be manipulated as required to remove the tongues 18 from said slot and thereby detach the strap 12 from said strap-supporting strip.

By the hereinbefore described construction it will be observed that my improved pipe-hanger is not only simple, strong and durable, but that all of the hereinbefore stated objects are successfully attained.

What I claim is—

55 1. A pipe-hanger comprising a metal strap which is adapted to extend under and form a seat for a pipe and has two opposite flexible portions arranged and contoured as required to embrace opposite sides respectively 60 of said pipe and spaced at their upper ends and each terminating at its upper end in an upwardly projecting arm, a supporting member which is adapted to support said strap and extends between the upwardly 65 projecting arms of said opposite portions of

the pipe-embraceable strap and is provided between said arms with a hole extending laterally through the strap-supporting member and having a bottom wall, and a collar adapted to hold said arms in close relation 70 to said strap-supporting member, each of said arms having a tongue which projects through the aforesaid hole and into the other of said arms and is adapted to rest on the aforesaid wall.

75 2. A pipe-hanger comprising a metal strap which is adapted to extend under and form a seat for a pipe and has two opposite portions arranged to extend transversely of opposite sides respectively of said pipe and each terminating at its upper end in an upwardly projecting flexible arm, a supporting member which is adapted to support said strap and extends between the upwardly projecting arms of said opposite 80 portions of the pipe-embraceable strap and has a hole formed between said arms and extending laterally through said strap-supporting member, and a collar arranged to hold said arms in close relation to said strap-supporting member, said strap-supporting member and said arms extending through said collar, said arms having tongues projecting through the aforesaid hole, and the collar being below said hole and movable 85 upwardly above said arms.

90 3. A pipe-hanger comprising a metal strap which is adapted to extend under and form a seat for a pipe and has two opposite flexible side portions arranged to extend transversely of opposite sides respectively of said pipe and spaced at their upper ends, a supporting strip which is adapted to support said strap and extends between the upwardly projecting arms of said side portions 95 of the pipe-embraceable strap and has a hole having a bottom wall and formed between said arms and extending laterally through the strap-supporting strip, each of said arms having a tongue which projects through said hole and is provided within 100 the other of said arms with a projection extending below said hole, each of said arms being apertured as required to accommodate the location of the tongue of the other of 105 said arms, and the tongue of each arm being formed by a laterally struck portion of said arm and trimmed or contoured as required 110 to form the aforesaid projection of said arm and arranged to be seated on edge on the 115 aforesaid wall.

120 4. A pipe-hanger comprising a metal strap which is adapted to extend under and form a seat for a pipe and has two opposite flexible side portions arranged and contoured as required to embrace opposite sides respectively of said pipe and each terminating at its upper end in an upwardly projecting arm, a substantially vertical supporting 125 strip which is adapted to support said strap 130

- and extends between the upwardly projecting arms of said side portions of the pipe-embraceable strap and has a rectangular slot extending endwise of and laterally through the strap-supporting strip, each of said arms having a tongue which projects through said slot and is provided within the other of said arms with a projection extending below said slot, the tongue of each arm being formed by a laterally struck portion of said arm and trimmed or contoured as required to form the aforesaid projection of said tongue, the tongues of said arms being side by side within said slot, and each tongue being in close proximity at its outer side to the adjacent side wall of said slot and adapted to be seated on edge on the bottom wall of said slot.
5. In a pipe-hanger, the combination, with a supporting strip, of a flexible metal strap which is adapted to extend under and form a seat for a pipe and has two opposite portions arranged to extend transversely of opposite sides respectively of said pipe and each terminating in an upwardly projecting arm, the upwardly projecting arms of said portions of the pipe-embraceable strap overlapping opposite sides respectively of the strap-supporting strip, said strap-supporting strip having a hole which extends laterally through said strip and has a bottom wall, each of the aforesaid arms having a tongue which projects through said hole and is adapted to rest on edge on said wall and provided within the other of said arms with a projection extending below said hole, said
- hole extending farther above the tongues of said arms than the projections of said tongues extend below said hole when the tongues rest on the bottom wall of said hole, and said projections having sloping surfaces facing downwardly and laterally toward the strap-supporting strip.
6. A pipe-hanger comprising a flexible metal strap which is adapted to extend under and form a seat for a substantially horizontal pipe and has two opposite portions arranged and contoured as required to embrace opposite sides respectively of the pipe and each terminating at its upper end in an upwardly projecting arm, a substantially horizontal collar-forming plate having an opening which extends through the plate and is formed substantially centrally of the plate and arranged to be engaged by the upwardly projecting arms of said opposite portions of the pipe-embraceable strap, and a supporting strip having a portion thereof extending between said arms, said arms extending through said opening and being in close relation to the strap-supporting strip, said portion of said strap-supporting strip being provided between said arms with a hole extending laterally through said strip, each of said arms having a tongue which projects through said hole in said strip and into the other of said arms, and the aforesaid plate being in close relation to and removable from said arms.
- In testimony whereof, I sign the foregoing specification, this 6th day of April, 1922.
- JOHN B. ESTEP.
